UNITED STATES PATENT OFFICE.

JOSEPH T. PARKER, OF WASHINGTON, DISTRICT OF COLUMBIA.

SUBMARINE VESSEL.

1,154,126.

Specification of Letters Patent. Patented Sept. 21, 1915.

Application filed June 2, 1915. Serial No. 31,786.

To all whom it may concern:

Be it known that I, JOSEPH T. PARKER, a citizen of the United States of America, and a resident of Washington, District of Columbia, have invented certain new and useful Improvements in Submarine Vessels, of which the following is a full and clear specification.

The object of this invention is to provide a vessel with a supplemental conning tower or lookout station at the bow for special use while the vessel is submerged, my invention being especially adapted for use on the long vessels that are now coming into use. In these longer vessels, the main or central conning tower is located a long distance from the bow or nose of the vessel and, therefore, even if it were provided with lookout windows for use when the vessel is submerged, it would not be effective in view of the fact that the distance one can see under water is necessarily considerably limited. By employing a supplemental conning tower and locating it close to the extreme forward end of the vessel and upon the upper side thereof, it will be possible for a person located in such supplemental conning tower to observe objects for a considerable distance ahead when the vessel is submerged, as more fully hereinafter set forth.

In the drawings—Figure 1 is a side elevation of a submarine vessel constructed in accordance with my invention; Fig. 2 is a plan view of the bow of the vessel; and Fig. 3 a vertical longitudinal sectional view of the bow portion of the vessel.

Upon the upper side of the vessel near its extreme forward end in the hull is formed an upwardly extending bulge *a* which forms a chamber in communication with the interior of the vessel, this chamber being sufficiently capacious to receive the head and shoulders of at least one member of the crew. This chamber is, of course, made water-tight, being in fact formed of a continuation of the hull or shell of the vessel. This tower-like bulge is provided at its front, sides and top with lookout windows *b*, these windows being of course air and water-tight and preferably being protected by a suitable grating *c*. This supplemental chamber or tower *a* tapers from its forward end upwardly and rearwardly to reduce resistance to a minimum. A member of the crew standing or sitting in a position where his head and shoulders will be in this sup-

plemental conning tower will have a view of the water ahead of and above the vessel when the vessel is submerged. Of course, it is understood that it will be impossible to see objects any considerable distance ahead of the vessel, but it will be possible to view objects, especially vessels on the surface of the water in the day time, sufficiently far ahead to render my invention highly useful in connection with certain kinds of submarine operations. For instance, with my supplemental lookout station at the extreme forward end of the vessel, it will be possible, if the vessel is moving slowly, as is usually the case when in the vicinity of mines or dangerous obstacles, to see the obstacles in time to avoid collision with them; and in other cases my supplemental lookout station will be of special service in assisting in discharging torpedoes when completely submerged and where the usual periscope is either out of commission or cannot be used by reason of the proximity to an enemy's surface vessel. It will be understood, of course, that I contemplate arranging suitable signal and control apparatus in proximity to the supplemental conning tower to enable the observer to control the vessel or give signals to the engineers to enable them to control the vessel.

In view of the possibility of crushing the glass panes or the tower itself and thus flooding the forward part of the vessel, it will be essential to provide means not only for the escape of the observer but also to prevent the main part of the vessel from being flooded. To accomplish this, I arrange, just back of the supplemental conning tower, a pair of separated partitions *d* and *e*, each provided with a doorway which is closed by a door *f*, preferably hinged at its upper end so as to gravitate into closed position. A hook or other device *g* may be provided for holding the forward door in open position, and the rear door will preferably be arranged to be normally closed. Suitable gaskets will be provided for insuring these doors being air and water-tight when closed. With this arrangement, in case of leakage or flooding of the forward part of the vessel, the observer will step into the chamber between the partitions and close the forward door, and then he can safely open the rear door and pass into the main part of the vessel. Even in case of a sudden and complete flooding of the supple-

mental conning tower compartment at the front, the normally closed door *f* will hold back the water until the observer has made his way into the air-lock compartment between the partitions and has closed the forward door, after which the rearward door may be safely opened even if the air-lock compartment be partly or wholly flooded, since with the forward door closed the pressure upon the rear door will be relieved sufficiently to enable the observer to open it with ease. In practice, it will be understood that the rear door will be kept closed at all times, while the forward door will preferably be held in open position, so that, in case of accident all the observer has to do is to take a step into the air-lock and release the forward door and thus prevent flooding or further flooding of the air-lock chamber.

Suitable means should be provided for supplying the observer with fresh air and also for pumping out any water that may accumulate in the air-lock compartment. Fresh air from the main compartments of the vessel may be pumped into the conning tower compartment through a pipe *h* which is preferably provided with a valve *i* to cut off back-flow of water in case the conning tower compartment is flooded. Vitiated air may be pumped out through a pipe *j* which is also preferably provided with a valve *k*. This pipe *j* may also be utilized for pumping flood water out of the air-lock chamber, and it will be understood, of course, that any other suitable device or apparatus may be employed to not only insure the comfort and safety of the observer, but also to prevent flooding of the supplemental conning tower

compartment from in any way seriously interfering with the usefulness or ability to manipulate the vessel in the usual way. It will be understood, of course, that the conning tower compartment shall be of such small capacity as compared with the size of the vessel that its complete flooding will not materially interfere with the handling of the vessel in the usual way. It will be understood that this supplemental conning tower may be duplicated at the stern of the vessel, which stern conning tower will be of value in maneuvering under water and especially in mine fields.

Having now particularly described and ascertained the nature of my said invention and in what manner the same is to be performed, I declare that what I claim is:

A submarine vessel provided with a supplemental conning tower compartment in its forward end, a conning tower communicating therewith and arranged on the upper side of the vessel and provided with lookout windows, air-lock means being provided between said compartment and the main compartment of the vessel, said means embodying separated partitions set back a distance from the tower and forming an air and water-tight chamber to the rear of the tower chamber, the innermost partition being provided with a normally closed door and the forward partition being provided with a door and means for holding the same open, and means for supplying fresh air past the normally closed door.

In testimony whereof I hereunto affix my signature.

JOSEPH T. PARKER.
